Nelson M. Howard

UNITED STATES PATENT OFFICE

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY

PRESSING MACHINE FOR USE IN THE MANUFACTURE OF BOOTS AND SHOES

Application filed December 30, 1927. Serial No. 243,702.

This invention relates to pressing machines for use in the manufacture of boots and shoes and is illustrated as embodied in a machine for pressing the joint or lap of the 5 welt of shoes to reduce the thickness of the welt at the joint in order that the shoe edge may be of substantially uniform thickness, thereby improving the appearance of the shoe.

10 In the manufacture of stitchdown shoes, particularly those of the smaller sizes, it is usual to turn outwardly the margin of the upper materials all the way round the shoe and to apply a false welt, so called, upon the 15 out-turned flange of the upper, the welt, of course, extending entirely around the shoe and being attached by a seam securing the outturned flange of the upper to a sole. This 20 sewing operation is always begun on the inner side of the shoe and continued completely around the periphery of the shoe. When, at the completion of the sewing operation, the end of the welt first attached is reached, it is necessary to form a joint at the ends of 25 the welt. Various common types of joint for uniting the ends of pieces without producing extra thickness at the joint may be employed, but these require more time and skill on the part of the operator than is justified by this class of work. Accordingly, it 30 is a common practice, after the welt has been sewed on completely around the shoe, to overlap the welt on the welt end already attached and to continue the seam for a few 35 stitches through both thicknesses of the welt the upper and the sole. The operator then stops the machine, draws the shoe away from the machine with the welt attached, and cuts off the welt through the last stitch made. In cutting off the welt the operator will sever 40 it at an angle so that the second end of the welt is beveled, the first end having been similarly beveled before attachment of the welt to the shoe. Of course, where the ends 45 of the welt overlap, there is a thicker appearance of the shoe edge which is objectionable. The term "welt lap" as hereinafter used is meant to include any form of welt lap such 50 that the joint is thicker than the remaining portion of the welt unless the term is shown

by the context to refer to the form of joint above described.

An object of this invention is to provide 55 improve means for pressing welt laps to improve their appearance and to reduce or eliminate abnormal shoe edge thickness at the welt lap.

In view of the foregoing, the invention provides a welt lap pressing machine comprising 60 a tool for engaging the upper surface of the welt lap, a support for engaging the bottom of the sole opposite to the welt lap, and means for effecting relative movement between the tool and support to compress the material adjacent to the welt lap to the normal thickness 65 of the shoe edge. Preferably and as illustrated, the tool is fixed and the support is moved relatively to the tool by a foot treadle having powerful leverage whereby the desired pressure may be applied to the 70 shoe materials between the tool and support. Also, as illustrated, the shoe support covers an area of the sole larger than the area of the 75 welt covered by the tool, so that the pressure applied will compress the welt without indenting or marring the bottom of the sole. In order that wear and strain on the shoe support may be equalized, the illustrated shoe support is made as a flat, circular disk with a portion of its periphery located under the 80 welt pressing tool, the disk being constructed and arranged for rotation so that various portions of its periphery may be brought into 85 position under the tool.

In presenting the shoe to the tool, the operator 90 may mar the upper by pressing it too hard against the tool or cause the tool to catch on a projecting seam of the upper. Also, when the pressure is applied the welt has a tendency to expand laterally outwardly of 95 the shoe. Accordingly, to meet these conditions the illustrated machine is provided with an abutment located on the welt engaging face of the tool which abutment is set back from the outer end of the tool a distance 100 corresponding to the normal width of the welt, or less, so that the operator, in presenting the shoe edge between the tool and support, will cause the edge of the welt at the welt lap to contact with the abutment as he

pushes it into position so that the shoe will be properly located without contact of the upper with the tool, and when pressure is applied the abutment will prevent the welt from being broadened laterally by the pressure.

These and other features of the invention will appear more fully from the following description when read in connection with the accompanying drawings and will be pointed out in the appended claims.

In the drawings,

Fig. 1 is a side view of a welt lap pressing machine embodying the invention;

Fig. 2 is a front view of a portion of the head of the machine;

Fig. 3 is a view of a shoe showing the welt lap before treatment by the machine; and

Fig. 4 is a view of a shoe showing the welt lap after treatment by the machine.

The illustrated machine is designed for pressing the welt lap of a stitchdown shoe in which the welt is carried around the shoe and the ends lapped one upon the other. In Fig. 1 the numeral 10 indicates a column to which is secured by screws 12 a head 14. On the upper end of the head is a surface 15 inclined at about thirty degrees from the vertical, to which surface a tool 16 is secured by a cap screw 18 and a dowel pin 20. The tool 16 is shaped at its lower end to enter the angle between the upper and welt of a shoe, its end being slightly curved to fit the curve of the upper at the shank portion of the shoe where the welt lap occurs. The tool is provided, on its lower face, with a flat welt engaging surface having a lateral extent sufficient to cover the lapped area of the welt. At right angles to the lower face of the tool 16 a long bearing is provided in the head 14 to receive a cylindrical stem 22 having at its upper end a disk-shaped head or enlargement 24 forming a table-like shoe support or pressing member to cooperate with the tool 16. The supporting head or table 24 covers a larger area on the bottom of the shoe than the tool does on the welt, the extended surface of the table preventing indenting or otherwise marring of the bottom of the shoe by the applied pressure. The stem 22 slides longitudinally in its bore in a direction perpendicular to the welt engaging face of the tool 16 and is formed to turn in its bearing so that by turning the disk 24 various portions of its periphery may be brought beneath the tool to equalize strain and wear on the head 24 of the stem 22. In presenting or withdrawing the work, the operator will usually cause the sole to engage the disk at one side or the other of its pivot so that the disk will be turned frequently to present different portions of its periphery beneath the tool. The disk is thus turned without special attention on the part of the operator.

The lower end of the stem 22 is rounded

and extends into an opening between the side walls of the head 14 in which is fulcrumed by a pin 26 an angle lever having a long horizontal arm 28 and a short arm 30 having a flat face 32 disposed substantially at right angles to the stem 22. The flat surface 32 is arranged to engage the lower end of the stem 22, the rounded formation of which reduces friction between the surface 32 and the stem and permits it to turn freely. The point of engagement of the stem 22 with the surface 32 is at a short distance from the fulcrum pin 26, so that the force applied at the end of the long arm 28 has a powerful mechanical advantage on the stem, the ratio of the lever arms in the illustrated machine being approximately three and one half to one. The outer end of the arm 28 is bifurcated to receive the upper end of the treadle lever 36 the lower end of which is pivoted at 38 to a treadle lever 40 fulcrumed at 42 on the column 10. The outer end of the lever 40 is provided, close to the rod 36, with a treadle (not shown) and is held raised by a spring 44. The treadle rod 36 is in two parts connected by a turn buckle 46 by turning which the length of the rod may be adjusted.

By reason of the powerful leverage provided by the difference in length of the lever arms 28, 30, an operator of average weight may, by applying, if desired, his entire weight to the treadle, produce a pressure of the work against the tool in excess of five hundred pounds, this pressure being applied by the work support in a direction perpendicular to the work engaging face of the tool 16.

On the welt engaging face of the tool 16 is provided an abutment 48 for the edge of the welt consisting of a plate somewhat thicker than the average welting and adjustably secured to the tool by a screw, so that its edge face will be presented to the edge face of the welt. The abutment 48 is located at a distance from the outer end of the tool 16 equal to or slightly less than the width of the welt.

The operator receives the shoe in the condition shown in Fig. 3, where it will be seen that one end of the welt has been lapped over the other end and two stitches taken through the two thicknesses of the welt, also that both ends of the welt have been cut off at an angle. In operating the machine the shoe is placed on the table 24 and moved inwardly of the machine to present the shoe so that the lapped portion of the welt will be located under the welt engaging face of the tool 16, the tool entering the angle between the upper and the welt. The edge face of the welt will engage the abutment 48 and may, if its edge projects too much, be forced inwardly of the shoe. The abutment is preferably set so that the operator cannot move the shoe far enough to cause the end of the tool 16 forcibly to engage the upper. The inclination of the

tool 16 and the table 24 enable the operator, in presenting the shoe to the machine, to observe the location of the welt lap, to locate the shoe relatively to the welt pressing 5 tool, and also to watch to good advantage the operation of the machine. The operator then depresses the treadle to apply downwardly directed force to the outer end of the long arm 28 and hence, through the short arm 30, 10 powerful pressure to the stem 22 to move it in a direction perpendicular to the welt engaging face of the tool and cause the work support 24 on the stem to apply pressure to an extended area of the shoe bottom and force 15 the welt lap against the smaller area of the welt engaging face of the tool 16. The pressure thus applied squeezes the projecting materials of the shoe edge and reduces their thickness, the reduction of thickness occurring 20 principally at the lapped end portions of the welt which are thus reduced in thickness so that the welt appears of uniform thickness throughout its extent. While the squeezing pressure is being applied, the abutment 25 48 holds the welt in place and prevents it from being squeezed out or broadened laterally of the shoe. In case the welt lap is difficult to reduce to the normal thickness of the welt, the operation may be repeated, and 30 in case of an unusually thick or particularly stubborn welt lap the shoe may be so located that only a portion of the lap will be between the pressing members, the operation being repeated and the shoe moved along 35 lengthwise of the welt to reduce the welt lap progressively.

Having thus described my invention, what I claim as new and desire to secure by Letters Patent of the United States is:

40 1. A machine for pressing the welt lap of a boot or shoe having, in combination, a tool having a flat surface for engaging the welt lap of a shoe, a support having a flat surface to engage the shoe bottom, and manually operated means having a great mechanical advantage for relatively moving the tool and support to apply heavy sustained pressure perpendicularly of the welt to all portions of the welt lap to cause the welt lap to be reduced in thickness.

45 2. A machine for squeezing the welt lap of a stitchdown shoe having, in combination, a tool to enter the angle between the side of the shoe and the welt and having a flat surface to engage the welt throughout the extent of the welt lap, a flat table for supporting the sole opposite the welt lap, and manually operated means arranged for powerful leverage to move relatively the tool and support to 50 squeeze the welt lap.

55 3. A machine for pressing the welt lap of a boot or shoe having, in combination, a tool for engaging a welt of a shoe and having a welt engaging surface of sufficient extent 60 lengthwise of the welt to engage the area of the

welt lap, said welt engaging surface being inclined at an angle to the vertical, a table for engaging the sole of the shoe opposite to the welt lap, said table being constructed and arranged to engage a larger area of the bottom 70 of the shoe than is engaged by the tool upon the welt, and means for increasing the effect of an applied force for relatively moving the tool and table to apply pressure to the sole and welt, the extended surface of the table 75 serving to prevent the pressure from marring the sole.

4. In a machine for pressing the welt lap of a stitchdown shoe in which the welt is carried entirely around the shoe and the ends lapped one upon the other, the combination of a tool having a flat lower surface to engage the welt and having a lateral extent sufficient to cover the lapped area of the welt, a sole engaging member having a flat surface parallel to the welt engaging face of the tool, and manually operated means constructed and arranged to apply heavy pressure through powerful leverage for relatively moving the tool and said sole engaging member in a direction perpendicular to their said work engaging surfaces to apply powerful sustained pressure to the material between them and to cause the lapped portions of the welt to be reduced in thickness.

5. In a machine for pressing the welt lap of a stitchdown shoe, the combination of a welt engaging tool, a table below the welt engaging tool and having its upper surface parallel to the welt engaging surface of the tool, a stem 100 on the table mounted for sliding movement in a direction perpendicular to the sole engaging face of the table, an angle lever having unequal arms mounted on a fixed axis, the shorter arm of the lever having a surface perpendicular to said stem and engaging the stem, and a treadle connected with the longer arm of said angle lever so that the table may be moved and powerful upward pressure may be exerted on the table.

6. A machine for pressing the welt lap of a boot or shoe having, in combination, a tool for engaging the welt and having sufficient extent lengthwise of the welt to cover the welt lap, a table for engaging the shoe bottom and having a stem perpendicular to the welt engaging face of the tool, an angle lever having unequal arms and mounted on a fixed axis, the shorter arm of the lever having a surface perpendicular to the stem and engaging the stem, and a treadle connected to the longer arm of the angle lever so that the table may be moved to apply powerful pressure to the shoe to squeeze the welt lap.

7. In a machine for pressing the welt lap 125 of a stitchdown shoe, the combination of a fixed tool member having a flat face to receive the welt lap and cover the extent of the welt lap, said face being inclined at approximately thirty degrees from the vertical, a circular 130

table beneath the said work receiving face of the tool and having a surface parallel to the face of the tool, said table having a cylindrical stem with a rounded lower end, said stem being mounted for free turning movement and for movement axially perpendicular to the face of the tool, a lever having a flat surface engaging the rounded end of the stem, and means for operating the lever to move the table toward the tool.

10. A machine for pressing the lapped ends of the welt of a stitchdown shoe having, in combination, a tool to engage the welt joint and having sufficient lateral extent to cover the lapped portions of the welt, an abutment to contact with the edge face of the welt and hold it inwardly of the shoe, a sole support for engaging the portion of the sole opposite the welt lap, and means arranged for powerful leverage for relatively moving the tool and sole support to apply powerful pressure to the welt lap.

15. A machine for squeezing the welt lap of a stitchdown shoe having, in combination, a tool to enter the angle between the side of the shoe and the welt to engage the welt lap, a table for supporting the sole opposite the welt lap, a gage on the welt engaging face of the tool to engage the edge face of the welt to prevent lateral broadening of the welt, and manually operated means arranged for powerful leverage to move relatively the tool and support to squeeze the welt lap.

20. A machine for pressing the lapped ends of the welt of a stitchdown shoe having, in combination, a tool constructed and arranged to enter the angle between the side of the shoe and the welt and having a welt engaging face, an abutment located to engage the edge 25 face of the welt to limit movement of the tool into the angle and prevent the tool from marring or catching on the upper, a support for engaging the sole of the shoe opposite to the tool, and means for relatively moving the 30 tool and support to apply perpendicular pressure to the welt lap to reduce its thickness.

In testimony whereof I have signed my name to this specification.

ANDREW EPPLER.
